(57) **CLAIM**

The ornamental design for a tray for filling of vials syringes and cartridges for fill and finish machines as shown and described.

DESCRIPTION

FIG. 1 is a bottom perspective view of a first embodiment of a tray for filling of vials syringes and cartridges for fill and finish machines showing our new design;

FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a top perspective view thereof;

FIG. 9 is another top perspective view thereof;

FIG. 10 is a third top perspective view thereof;

FIG. 11 is a bottom perspective view of a second embodiment of a tray for filling of vials syringes and cartridges for fill and finish machines showing our new design;

FIG. 12 is a top view thereof;

FIG. 13 is a bottom view thereof;

FIG. 14 is a front view thereof;

FIG. 15 is a back view thereof;

FIG. 16 is a right side view thereof;

FIG. 17 is a left side view thereof;

FIG. 18 is a top perspective view thereof;

FIG. 19 is another top perspective view thereof;

FIG. 20 is a third top perspective view thereof;

(Continued)

FIG. 21 is a bottom perspective view of a third embodiment of a tray for filling of vials syringes and cartridges for fill and finish machines showing our new design;
 FIG. 22 is a top view thereof;
 FIG. 23 is a bottom view thereof;
 FIG. 24 is a front view thereof;
 FIG. 25 is a back view thereof;
 FIG. 26 is a right side view thereof;
 FIG. 27 is a left side view thereof;
 FIG. 28 is a top perspective view thereof;
 FIG. 29 is another top perspective view thereof;
 FIG. 30 is a third top perspective view thereof;
 FIG. 31 is a bottom perspective view of a fourth embodiment of a tray for filling of vials syringes and cartridges for fill and finish machines showing our new design;
 FIG. 32 is a top view thereof;
 FIG. 33 is a bottom view thereof;
 FIG. 34 is a front view thereof;
 FIG. 35 is a back view thereof;
 FIG. 36 is a right side view thereof;
 FIG. 37 is a left side view thereof;
 FIG. 38 is a top perspective view thereof;
 FIG. 39 is another top perspective view thereof; and,
 FIG. 40 is a third top perspective view thereof.
 The broken lines and the half-tone shaded area within the broken lines depict portions of the tray for filling of vials syringes and cartridges for fill and finish machines that form no part of the claimed design.
